CLAIM

The ornamental design for a toilet seat for a child, as shown and described.

DESCRIPTION

FIG. 1 is a top perspective view of a toilet seat for a child showing our new design;
FIG. 2 is front elevational view thereof;
FIG. 3 is a left side elevational view thereof, the right side being a mirror image of the left side;
FIG. 4 is a rear elevational view thereof;
FIG. 5 is a top plan view thereof; and,
FIG. 6 is a bottom plan view thereof.
